UNITED STATES PATENT OFFICE.

ROBERT HILLS ALEXANDER, OF WILLINGTON QUAY, AND THOMAS GRAHAM, OF SUNDERLAND, ENGLAND.

SHIP'S DAVIT.

1,389,338.

Specification of Letters Patent. Patented Aug. 30, 1921.

Application filed February 20, 1920. Serial No. 360,082. Renewed July 23, 1921. Serial No. 487,132.

To all whom it may concern:

Be it known that we, ROBERT HILLS ALEXANDER, residing at Willington Quay, and THOMAS GRAHAM, residing at Sunderland, both in the county of Durham, England, subjects of the King of England, have invented certain new and useful Improvements in Ships' Davits, of which the following is a specification.

10 This invention relates to improvements in ships' davits of the kind in which the boat is slung from a single curved davit arm pivoted at its lower end for swinging movement inboard and outboard and comprising

15 screw gear for effecting such movement and suitable winding gear with tackle for raising and lowering the boat, the present invention consisting in certain novel features and combinations of parts as hereinafter described and claimed.

The improved ship's davit constructed according to this invention comprises a single curved supporting arm or jib formed so that its upper or outer portion is comparatively narrow and slender as seen transversely to the longitudinal axis of the ship on which it is assumed to be mounted, and toward its lower end it is splayed out in both directions so as to form a laterally extended frame on which boat supporting chocks may be mounted, there being ample space between the chocks to give support to the boat fore and aft. The arm is so curved as to clear the mid section of the boat when inboard and so that the latter may have its center of gravity well inward of the axis of the arm. The arm is pivoted on widely separated centers substantially beneath the respective chocks. It is provided with two

40 pairs of chocks, one of each pair substantially parallel with the arm, and the other of each pair extending forwardly at an angle. The clearance between the arm and the boat is thus reduced to a minimum when

45 the boat is in inboard position. The arm is mounted on a pivotal axis so that the point of suspension of the tackle is vertically above the center line of the boat when inboard.

50 The tilting of the arm is advantageously effected by a screw gear operating a sliding member connected by a link to the arm and the tackle by a winch carried by the said member.

Referring to the accompanying drawings 55 illustrating an embodiment of the invention:

Figure 1 is a side elevation showing a davit in normal position.

Fig. 2 is a similar view showing the davit 60 tilted outboard in the launching position.

Fig. 3 is a rear view.

Fig. 4 a side view showing boats on two decks adapted to be operated by one davit, and

65 Fig. 5 is a plan showing means for connecting the fall to the boat.

a designates the arm of jib pivotally connected to the deck at *b* and provided at its upper end with a pulley *d*, said arm being 70 advantageously built up as shown in Fig. 3 of two members *e f* suitably connected by ties. Connected to the arm on each side are a pair of brackets *g g¹* forming chocks for the boat, one of said bracket members *g¹* 75 being preferably pivotally connected at *g²* to its neighbor as shown, so that by releasing a pin *i* it can be dropped to give access to the bottom of the boat. Mounted in a frame *h* behind the arm *a* is a worm *j* adapted to be rotated by a handle *j¹*, said worm having thereon a nut *k* connected to a carriage *l* which is suitably mounted on the frame *h* and connected to the arm *a* by a link *m*. On the carriage is mounted a winch 85 *n* from the drum of which a rope *o* passes over a pulley *d* to a pulley block *p*, the latter carrying a hook *q* of the self-releasing type which is adapted to be connected to a sling attached to the boat, one form of sling 90 being shown by way of example in Fig. 5 in which the sling ropes *s* are connected to lugs *s¹* pivoted on the boat's keel.

In Fig. 4 the davit is shown mounted on a boat deck and another boat supported on 95 chocks *t* on the deck below. In this case a slot is cut in the deck on which the davit stands to allow the tackle to be lowered and the hook to be attached to the boat below after the upper one has been lowered.

100 The screw gear *j k* and the winch may be power operated if desired, or provision may be made for both hand and power operation.

105 In operation, when it is desired to lower the boat, the hook is attached to the slings. The falls are tautened by the winch *j* so as to raise the boat from the chocks. The arms

are then moved outward on their pivots by the screw gear *f g*. The boat is then lowered by the winch.

A davit made in accordance with this invention can be easily and quickly manipulated. The distance between the boat and the side of the vessel can be altered during launching, and all danger resulting from the tackle jamming in the blocks is avoided, 10 and further as shown two or more boats can be lowered by one operation.

What we claim as our invention and desire to secure by Letters Patent of the United States is:—

- 15 1. In a ship's davit the combination of a single curved davit arm broadened in each direction internally toward its pivotal axis, its curvature being such that when inboard, the pivotal axis is exterior of the vertical plane containing the longitudinal center line of the boat and the extremity of the arm in said vertical plane two laterally widely spaced bearings attached to the ship's deck carrying said pivotal axis, and lifting tackle 20 for the boat carried by the extremity of the arm.
2. In a ship's davit the combination of a single curved davit arm broadened laterally toward its pivotal axis, its curvature being 30 such that when inboard, the pivotal axis is exterior of the vertical plane containing the longitudinal center line of the boat and the extremity of the arm in said vertical

plane, laterally spaced bearings carrying said pivotal axis, and lifting tackle for the 35 boat carried by the extremity of the arm, together with a couple of pairs of chocks carried by the lateral extensions respectively of said arm, one chock parallel to the arm and the other chock projecting therefrom 40 at an angle, to support a boat thereon.

3. In a ship's davit the combination of a single curved davit arm broadened laterally toward its pivotal axis, its curvature being 45 such that when inboard the pivotal axis is exterior of the vertical plane containing the longitudinal center line of the boat and the extremity of the arm in said vertical plane, laterally spaced bearings on the ship's deck carrying said pivotal axis, a horizontal slide- 50 way attached to the deck rearward of said arm, a winch frame rearward of said arm and movable on said slideway, lugs on said arm and winch frame respectively, a link connecting said lugs, a winch in winch 55 frame, boat lifting tackle operated by said winch, and means for reciprocating said winch frame on said slide way.

In witness whereof we have signed this specification in the presence of two witnesses. 60

ROBERT HILLS ALEXANDER.
THOMAS GRAHAM.
